UNITED STATES PATENT OFFICE.

SAMUEL HENRY COUCH AND WILLIAM WEIR HENRY, OF WOLLASTON, AND ALTON E. STEVENS, OF ATLANTIC, MASSACHUSETTS, ASSIGNEES TO S. H. COUCH CO. INC., OF ATLANTIC, MASSACHUSETTS.

ANNUNCIATOR-DROP.

1,134,996.

Specification of Letters Patent. Patented Apr. 13, 1915.

Application filed July 28, 1911. Serial No. 641,167.

To all whom it may concern:

Be it known that we, SAMUEL H. COUCH and WILLIAM WEIR HENRY, of Wollaston, and ALTON E. STEVENS, of Atlantic, in the county of Norfolk and State of Massachusetts, all citizens of the United States, have invented certain new and useful Improvements in Annunciator-Drops, of which the following is a specification.

10 The object of this invention is to produce an annunciator drop for use in selective ringing and announcing systems which is reliable and sure in its action. The invention introduces several novel features which 15 are correlative in producing this result, although our device is operative with but a part of them, as will be explained.

In the drawings, which illustrate our invention and form part of this specification,—Figure 1 is a front view of one unit 20 adapted to form part of a system, the operating means being shown diagrammatically. Fig. 2 is an edge view of same. Fig. 3 is a mid-vertical section, with disk in vertical 25 position. Fig. 4 is an end view of same. Fig. 5 is an edge view of the armature.

The base 1 supports an ordinary electro-magnet 2 by means of the lip 3 and screws 4. The armature 5 is pivotally mounted on 30 stud or post 6, and one of the ears 7 has a bent prong 8 adapted to engage slot 9 in disk 10 which is also pivotally mounted on post 6. Slot 9 is adapted to limit the throw of disk 10, and the mechanism above described, 35 with the operating system 11, makes a complete annunciator drop unit as comprised in our invention, although, as will be later explained, different elements can be substituted for some of the foregoing, without de- 40 parting from the spirit of our invention. In practice, we find it preferable to provide an auxiliary stop which may co-act with the limiting means of slot 9, or be, in itself, the sole and compelling means for limiting 45 the throw of disk 10. A rigid and unyielding stop might encourage an occasional re-bound of the disk, and experiment has proven this to be the case. On the other hand, an elastic stop is unsuitable for the 50 same reason. We have, therefore, provided a stop or stops 12, formed of soft, cold-rolled steel and secured in an offset position to the base 1 by means of the same screws 4 which secure the electro-magnet 2. The

nature of the material forming the stops 12 55 is such as to deaden the resilient or elastic effect of the impact of disk 10, while its offset support permits a slight yielding action which further prevents the tendency to rebound. Another means for preventing the 60 rebound of disk 10 is shown in the drawings which consists of an auxiliary disk or drag 15, said drag being loosely mounted on pin 16. The enlarged opening 17 in drag 15 permits said drag to lag behind disk 10 65 during its throw, and when the limit of throw has been reached by disk 10, the drag 15 catches up and comes to a stop at the precise moment when any rebound tendency of disk 10 is most effective. The impact of 70 drag 15, therefore, serves to interrupt the rebound vibrations of disk 10, and this insures reliability of action in the drop. Either one of these several means is believed to be practically effective alone, but we prefer to incorporate them all in our preferred 75 form, as they all add to the effect sought.

We prefer to provide a German silver washer 18 between base 1 and armature 5 to check any tendency of magnetic drag in the 80 latter.

What we claim is:—

1. An indicator adapted to be thrown from a position of rest, means for causing such throw, and a stop adapted to receive 85 the impact of the blow; in combination with a drag loosely mounted on said indicator in such fashion that it will travel in unchanged relation with it until the stop checks the indicator movement, whereupon said drag is 90 free to continue its bodily advance through the space permitted by the loose mounting.

2. An indicator adapted to be thrown from a position of rest, means for causing such throw, and a stop adapted to receive 95 the impact of the blow; in combination with a drag mounted on said indicator and adapted to be moved therewith to the time of said impact, and thereafter to be advanced by its momentum bodily with respect to said indicator, through a limited 100 space.

3. An indicator adapted to be thrown from a position of rest, means for causing such throw and means for limiting the movement of said indicator; in combination with a drag so mounted in connection with said indicator that it shall be moved by the lat- 105

ter in unchanged relation therewith to the end of said movement, means whereby said drag shall thereafter be permitted a slight continued bodily advance with respect to 5 said indicator, and means whereby said indicator shall limit this latter movement.

4. An indicator adapted to be thrown from a position of rest, means for causing such throw, and a stop adapted to receive 10 the impact of the blow; in combination with a drag so mounted in connection with said indicator that it shall travel therewith in

unchanged relation thereto to the time of impact and thereafter shall deliver its own impact to prevent rebound of said indicator. 15

In testimony whereof we have affixed our signatures, in presence of two witnesses.

SAMUEL HENRY COUCH.
WILLIAM WEIR HENRY.
ALTON E. STEVENS.
